UNITED STATES PATENT OFFICE.

FREDERICK LEADBEATER, OF DETROIT, MICHIGAN.

VALVE.

1,076,895.

Specification of Letters Patent.

Patented Oct. 28, 1913.

Application filed June 4, 1912. Serial No. 701,434.

To all whom it may concern:

Be it known that I, FREDERICK LEADBEATER, citizen of the United States, residing at Detroit, county of Wayne, State of Michigan, have invented a certain new and useful improvement in Valves, and declare the following to be a full, clear, and exact description of the same, such as will enable others skilled in the art to which it pertains to make and use the same, reference being had to the accompanying drawings, which form a part of this specification.

My invention relates to an improvement in valves, shown in the accompanying drawings and more particularly set forth in the following specification and claims.

My invention provides for the elimination of the usual stuffing box packing around the valve stem, a steam tight joint being secured by providing the valve stem with a disk adapted to be drawn to its seat in the wall of the valve bonnet, the disk providing an extended surface along the stem so constructed and arranged that it may be forced into intimate relation therewith.

Another feature of the invention consists in jointing the stem adjacent to the disk whereby any lateral movement of the valve stem resulting from the operation of the handle controlling the stem, will not cause the disk to tilt and thus permit the steam to escape along the stem which may result in scalding the hand of the operator.

Another feature of the invention consists in providing a thimble sleeved on the valve stem having a screw-threaded engagement with the valve bonnet, a spring being housed within the thimble one end of which bears against the wall of the thimble and the other against a shoulder carried by the valve stem whereby upon adjusting the thimble the tension of the spring may be regulated to force the disk carried by the valve stem against its seat in the valve bonnet,—the construction being such that the tension of the spring may be adjusted without removing any of the parts.

Other advantages and improvements will hereafter appear.

In the drawings accompanying this specification:—Figure 1 is a central sectional view through the valve, with parts broken away and in elevation. Fig. 2 is a detail view of the connecting portion of the valve stem, partly in elevation and in section to

more clearly show the construction. Fig. 3 is a fragmentary detail view, with parts in section, showing a modification in which a shoulder is secured to the stem against which one end of the spring sleeved within the thimble bears.

Referring now to the letters of reference placed upon the drawings:—A denotes the body of the valve; B its seat; C the valve bonnet having the usual screw-threaded connection with the valve body.

D indicates the upper end of the valve stem provided with a handle D' for operating it.

D² denotes the lower part of the valve stem having an enlarged portion D³ provided with a socket d to receive the end of the upper portion of the stem.

d' is a transverse pin connecting the upper and lower portions of the stem together,—75 the aperture to receive the pin in one portion being preferably larger in diameter than the pin, as indicated at d², permitting a slight lateral movement between the parts.

D⁴ is a flange projecting from the enlarged portion D³ having an upstanding annular rim d².

G is an annular disk, preferably formed of composition or metallic packing, sleeved on the stem and housed within the upstanding rim of the flange D⁴. 85

d⁴ is an annular V-shaped rib projecting from the flange D⁴ into a recess provided for its reception in the disk G.

The upper wall of the disk G near its 90 outer periphery, is formed with a flanged surface adapted to bear against an annular seat C' depending from the inner wall of the bonnet C. The disk G is formed with a cone-shaped portion g providing an extended bearing surface along the valve stem; 95 against the outer face of which the inwardly projecting flange portion c² of the bonnet bears to force the disk into sealing contact with the stem.

E indicates a valve, and E' the valve disk formed of suitable material.

F is a traveling nut having a screw-threaded engagement with the lower end of the valve stem D², it being free to reciprocate on the stem but held against rotation by guides c projecting from the inner wall of the bonnet C.

H is an annular thimble having a screw-threaded engagement with the upper part of 110

the bonnet and having an opening through its lower wall for the passage of the valve stem.

H' is a spring sleeved on the valve stem 5 and housed within the thimble H.

h, h, are washers sleeved on the stem above and below the spring.

I is an adjustable nut having a screw-threaded engagement with the valve stem, 10 the threads preferably running in an opposite direction to those of the thimble H.

In the modification shown in Fig. 3, the adjustable nut I is dispensed with, a projecting rim or flange J, carried by the stem 15 being provided serving as an abutment against which the spring bears when put under tension by the adjustment of the thimble H.

Having indicated the several parts by 20 reference letters, the construction and operation of the valve will be readily understood.

By operating the handle D' in the usual manner, the valve may be raised or forced 25 to its seat B through the action of the traveling nut F; the passage through the ports A' and A² being thus controlled. By adjusting the nut I or the thimble H, either jointly or separately, the tension of the spring H' 30 may be regulated and the disk G held upon its seat. The spring H' co-acting with the nut I and the flange portion c² serves to force the disk G into sealing contact with the valve stem thus providing against leakage 35 around the stem. Should there be a slight lateral movement of the handle caused for example by the operator adjusting the valve, any tendency it might have to tip the disk G would be absorbed at the jointed connection 40 between the upper and lower portions of the valve stem,—it being obvious that as the pin d' is slightly smaller in diameter than the aperture through which it engages one portion of the stem, a slight lateral movement is provided for without ef- 45

fecting the seating of the disk. By forming the flange D⁴ with an upstanding rib d⁴ the joint between the disk and flange is broken, thus further assisting in securing a tight joint between the parts.

Having thus described my invention, what I claim is:—

1. In a valve, a body portion provided with a valve seat, a stem for actuating the valve formed in two parts and joined together, a flange integral with one portion of the stem, a disk carried by said flange having a cone-shaped upper wall tapering toward the stem, a bonnet secured to the body portion through which the stem projects having a flange provided with an annular seat for the disk and adapted to bear against the cone-shaped upper wall of the disk to force it against the stem, a thimble having a screw-threaded engagement with the bonnet and provided with an aperture through which the stem projects, a spring housed within the thimble and sleeved upon the stem, and an adjustable nut engaging the stem adapted to regulate the tension of the 55 spring.

2. In a valve, a body portion provided with a valve seat, a stem for actuating the valve formed of two parts and connected together by a transverse pin, a flange integral with one portion of the stem, a disk carried by said flange, a bonnet secured to the body portion through which the stem projects having an annular seat to receive the disk, a thimble sleeved on the stem and having a 60 screw-threaded engagement with the bonnet, a spring housed within the thimble, and an adjustable nut engaging the stem adapted to regulate the tension of the 65 spring.

In testimony whereof, I sign this specification in the presence of two witnesses.

FREDERICK LEADBEATER.
